UNITED STATES PATENT OFFICE.

JOHN C. WHITRIDGE AND GEORGE T. JOHNSON, OF COLUMBUS, OHIO, ASSIGNEES TO
THE BUCKEYE STEEL CASTINGS COMPANY, OF COLUMBUS, OHIO.

SIX-WHEEL TRUCK.

1,153,741.

Specification of Letters Patent. Patented Sept. 14, 1915.

Application filed July 20, 1915. Serial No. 40,903.

To all whom it may concern:

Be it known that we, JOHN C. WHITRIDGE and GEORGE T. JOHNSON, citizens of the United States, and residents of Columbus, 5 in the county of Franklin and State of Ohio, have invented certain new and useful Improvements in Six-Wheel Trucks; and we do hereby declare the following to be a full, clear, and exact description of the invention, such as will enable others skilled 10 in the art to which it appertains to make and use the same.

Our invention relates to an improvement in six wheel trucks for railway cars, and 15 particularly to the central bolster member thereof which carries the body of the car.

The object of the invention is to provide a main bolster having a center bearing to receive the load of the body of the car and 20 transmit the same to the auxiliary bolsters at the centers of the length of the latter, and the invention consists in the parts and combinations of parts as will be more fully described and pointed out in the claims.

25 In the accompanying drawings, Figure 1 is a view in plan of a six wheel truck embodying our invention, the truck side frames being omitted; Fig. 2 is a view in side elevation of the same; Fig. 3 is a view in transverse section through the truck, showing at one side parts of the truck side frames in section; Fig. 4 is a view in side elevation of the main bolster; Fig. 5 is a view of same in plan; Fig. 6 is a view in bottom plan and 30 Figs. 7, 8 and 9 are views in section on the lines A—B; C—D and E—F of Fig. 6.

The main bolster 10 is designed especially for heavy loads and in order to secure the necessary strength, it must have sufficient 40 depth at its central portion, or in the vertical plane of the middle axle of the truck, and to secure the necessary depth without interfering with said middle axle, the bolster is provided with a central opening or passageway 16 for the free passage and movement of the middle axle 11 of the truck, the top of said opening or passageway being closed by a part 12 carrying the center bearing 13, which is removable so as to permit 45 the axle to be placed in position and removed when necessary.

The bolster 10 resembles an ordinary cast steel truck side frame, in that it is deeper at the center than at the ends, and is made of 50 two parts 10 and 12. The part 10 is hollow

and provided with openings 14 in its sides, and internally with ribs 15, shown in dotted lines in Figs. 4 and 5 which stiffens the structure at the parts subjected to the greatest strains. The part 12 of the bolster which 60 carries the center bearing, is secured centrally to the main section 10 thereof and forms a closure for the axle opening 16 in the latter. This part 12 of the bolster is set into the main section 10, and has horizontal bearings 17 and 18 which serve to carry the vertical load, and vertical shoulders or abutments 19 and 20 which operate to take care of the compressive stresses and thus prevent a collapse of the bolster. The 65 bottom member of the bolster 10 is subjected to tensile or pulling stresses, while the upper member 12 thereof is subjected to compressive stresses, and the latter are taken care of by the horizontal bearings and shoulders so 70 as to prevent the strains from falling on the bolts 21 which secure the part 12 to the main body of the bolster.

The bolster 10 extends lengthwise the 75 truck and is mounted at its ends on seats 80 formed on or in the auxiliary bolsters 22 and 23. These bolsters 22 and 23 extend transversely of the truck one being located in a plane between the front axle 24 and the middle axle 11, and the other in a plane 85 intermediate the middle axle 11 and rear axles 25, and each is preferably provided with an opening located centrally with relation to its ends, for the reception of the 90 ends of the main bolster 10. The ends 26 of this bolster have flattened and parallel 95 upper and lower faces, as shown in Fig. 4 and each end is provided with the depending integral lugs 27 adapted to overhang the end bolsters and secure them to the central 100 bolster.

While the main bolster may rest on the 105 tops of the auxiliary bolsters, we prefer to mount them in openings formed in said auxiliary bolsters as previously explained, in order to conserve space and bring all the bolsters into proper relation with each other and also with the central axle, which is very important, as the vertical distance from the rail is limited within which to locate the bolster structure of the necessary strength, and provide for the necessary clearance above the rails, without elevating the car body above the prescribed level.

The ends of the main bolster 10 having 110

integral lugs thereon interlocks with the auxiliary bolster, so that the weight of the main bolster and its load are sufficient to retain the former in position without any 5 additional securing devices.

We have not shown or described the construction of truck side frames as our improvement is applicable for use with any that may be used on a six wheel truck.

10 It is evident that many slight changes might be resorted to in the relative arrangement of parts shown and described without departing from the spirit and scope of our invention. Hence we would have it understood 15 that we do not wish to confine ourselves to the exact construction and arrangement of parts shown and described, but

Having fully described our invention what we claim as new and desire to secure by 20 Letters-Patent, is:—

1. In a six wheel truck, the combination of auxiliary bolsters extending transversely of the truck, a main bolster supported at its ends on the auxiliary bolsters and provided 25 with an opening for the passage of the middle axle, the said opening being open at the top, and a removable portion forming a top closure for said opening.

2. In a six wheel truck, the combination of auxiliary bolsters extending transversely of the truck, a main bolster supported at its ends on the auxiliary bolsters and provided with an opening for the passage of the middle axle, the said opening being open at the top, and a removable portion forming a closure 30 for said opening, and the center bearing for the car body.

3. In a six wheel truck, the combination

of a main bolster extending lengthwise the truck and provided with a transverse passage way for the middle axle the said passage way being open at the top, auxiliary bolsters forming supports for the ends of the main bolster and a removable center bearing closing the passage way in the main 40 bolster at the top, and having shoulders that engage shoulders on the bolster.

4. In a six wheel truck, the combination of a bolster having a deep center and narrowed ends and provided with a central 50 transverse passage way for the middle axle, the said bolster extending lengthwise the truck, auxiliary bolsters arranged transversely of the truck and supporting the ends of said main bolster and a removable member 55 forming a closure for the top of the transverse opening in the longitudinal bolster, and also carrying the center bearing for the car body.

5. In a six wheel truck, the combination 60 of transverse bolsters and a main bolster extending longitudinally of the truck and having interlocking connection with and carried at its ends by said transverse bolsters, the said main bolster having an opening 65 through same for the passage of the middle axle of the truck.

In testimony whereof, we have signed this specification in the presence of two subscribing witnesses.

JOHN C. WHITRIDGE.
GEORGE T. JOHNSON.
